UNITED STATES PATENT OFFICE.

LEVI H. ROBERTS AND CHARLES E. SANFORD, OF INDIANAPOLIS, INDIANA,
ASSIGNORS TO E. C. ATKINS & COMPANY, OF SAME PLACE.

BUCKSAW-FRAME.

SPECIFICATION forming part of Letters Patent No. 395,294, dated December 25, 1888.

Application filed January 3, 1888. Serial No. 259,552. (No model.)

To all whom it may concern:

Be it known that we, LEVI H. ROBERTS and CHARLES E. SANFORD, citizens of the United States, residing at Indianapolis, in the county 5 of Marion and State of Indiana, have invented certain new and useful Improvements in Bucksaw-Frames, of which the following is a specification.

The object of our said invention is to provide a double brace for the frames of buck-saws, arranged in such a manner that said frames will be rendered very stiff, and also by which they may be tightened and adjusted, as will be hereinafter more fully described and 15 claimed.

Referring to the accompanying drawings, which are made a part hereof, and on which similar letters of reference indicate similar parts, Figure 1 is a side elevation of a saw 20 embodying our said invention; and Fig. 2 is a central longitudinal section of so much of the frame as relates to our particular invention, on an enlarged scale.

In said drawings the portions marked A 25 represent the saw; B, the end pieces of the frame, and C the brace, which constitutes the subject-matter of our present invention. The saw A and end pieces of the frame B are not peculiar in their construction, said saw being 30 mounted between the front ends of said end pieces and their rear ends being connected by an ordinary tightening rod or brace, B', in the usual manner.

The brace C is formed with an elliptical 35 opening at its center, it preferably being constructed of two parts of equal rigidity, each end of both of which parts of equal rigidity is curved outwardly and the center of which is also curved outwardly, said two parts 40 being placed so that their ends curve in opposite directions and their centers being so curved as to form the ellipse above mentioned, the bearing-points being intermediate between these two portions, where the 45 two parts are secured together by rivets c', loosely mounted in suitable perforations provided at these points. The ends of the brace are each tenoned and mounted in suitable mortises in the end pieces, B, the two parts 50 so entering said mortises as to brace against

each other. At the center of the brace is mounted a screw-threaded bolt, c, extending through both parts and provided with a thumb-nut on the back side of the brace, a washer being mounted between said nut and 55 said brace, as shown.

While it is preferred that the brace be formed in two parts and secured together loosely, so that one part may be capable of a slight independent motion, thus insuring that 60 the strain upon the respective parts shall be perfectly equalized, yet it will be understood that said brace may be formed of a solid piece with the elliptical opening sawed out if, for any reason, it should seem desirable, without 65 departing from our invention, which principally consists in the formation of the brace by which it is rendered elastic or made capable of being extended or lengthened as a whole, and the frame thus made stiff and 70 secure.

The use and operation of our invention are as follows: The brace being in position for use in the frame, as shown in Fig. 1, and the saw being tightened by means of the rod B', 75 the two parts of the brace operate in bearing against each other at the points where they come in contact to force the ends apart, thus tending to stiffen and brace the saw and prevent it from getting loose or the joints from 80 becoming worn, as has been the case with frames of the old construction; also, when the rear ends of the end pieces, B, have been drawn to the position desired in relation to 85 each other, if the saw shall not be sufficiently tight the operator may tighten it in this position by screwing down the thumb-nut on the bolt c, which tends to force the central part of the brace together and forces its ends outwardly, making it longer and securely tightening all the joints with but very little effort; 90 also, when the saw shall have been tightened as tight as possible by means of the brace-rod B', if it is desired that it shall be made still more tight it will be found an easy matter to screw down the nut on the bolt c, thus securing a firmness and stiffness to the frame which it is impossible to secure with the old construction.

Having thus fully described our said inven- 100

tion, what we claim as new, and desire to secure by Letters Patent, is—

1. In a saw-frame, the combination of the end pieces, and a brace, C, formed of two substantially equal parts curved away from each other at the ends and center, and each end of each part secured in position to brace against one of said end pieces, the two parts of said brace being arranged to brace against each other, and the means for forcing said two parts toward each other at the center, substantially as set forth.

2. The combination of the saw A, the frame B, and the brace C, formed of two substantially equal pieces mounted to bear against each other and curved away from each other at the ends and center, each end of each of

said pieces being mounted in and arranged to brace against one of the end pieces of the frame, and the bolt c, extending through the center of both pieces of said brace and provided with a thumb-nut, whereby the centers of said pieces may be forced toward each other, substantially as described, and for the purposes specified. 25

In witness whereof we have hereunto set our hands and seals, at Indianapolis, Indiana, this 29th day of December, A. D. 1887.
